E. F. SPAULDING,
DRINKING CUP,
APPLICATION FILED JULY 9, 1913.

1,180,330.

Patented Apr. 25, 1916.

UNITED STATES PATENT OFFICE.

ELIJAH F. SPAULDING, OF BROOKLYN, NEW YORK.

DRINKING-CUP.

1,180,330.

Specification of Letters Patent. Patented Apr. 25, 1916.

Application filed July 9, 1913. Serial No. 777,989.

To all whom it may concern:

Be it known that I, ELIJAH F. SPAULDING, a citizen of the United States, and a resident of Brooklyn, in the county of Kings and State of New York, have invented certain new and useful Improvements in Drinking-Cups, of which the following is a specification.

The invention pertains more particularly to drinking cups made of paper or equivalent material intended to be thrown away after being used by one person.

One object of the invention is to provide a paper drinking cup which is initially flat so as to be capable of being readily carried in the pocket, but which may, at its lower end, be readily manipulated by the user so as to convert the flat cup into a cup having distended sides and a flat bottom capable of supporting the cup and its contents on a table or the like.

A further object of the invention is to provide a paper drinking cup which is entirely devoid of pasted seams.

A further object of the invention is generally to provide a paper drinking cup of such durable character, although at small expense, that it may be very safely and conveniently used for its intended purposes.

In carrying out my invention I form the body of the cup from a single blank folded transversely across its center to form two corresponding flat sides and secure the adjacent side edges of said sides together by metal binding strips extending from the upper edge to the lower edge of the cup and clamping the facing edges of the sides of the cup together and initially forming a flat cup whose two sides are close against each other. The blank from which the flat cup is made is formed with special crease lines which are readily discernible in the flat cup and on which lines the user may fold the lower end portions of the cup to create a flat bottom of definite shape and permanent character and capable of supporting the cup with its contents on a table or the like for an indefinite period.

The invention will be fully understood from the detailed description hereinafter presented, reference being had to the accompanying drawings, in which:

Figure 1 is an elevation of the outer face of the paper blank from which my cup is formed, the central transverse dotted line denoting the line on which the blank is

folded in the formation of the flat cup, and the other dotted lines indicating the lines on which the lower end of the cup may finally be folded by the user to create a flat bottom not only to support the cup but to hold the sides thereof apart so that the cup may be conveniently filled and used; Fig. 2 illustrates the blank as having been folded and with the metal binding strips applied to the opposite edge portions thereof and extending slightly above the same; Fig. 3 is a horizontal section through one edge portion of the same on the dotted line 3—3 of Fig. 2; Fig. 4 is a side elevation of the completed cup, the transformation of the structure shown in Fig. 2 to that shown in Fig. 4 comprising the folding inwardly or toward each other against one face of the cup of the two metal binding strips and the bending laterally and downwardly of the projecting upper ends of said strips against the inner surface of the side of the cup against which the strips are folded; Fig. 5 is a vertical section through a portion of the upper end 81 of the cup on the dotted line 5—5 of Fig. 4, and showing the upper end of the binding strip as having been folded inwardly against the inner face of one side of the cup; Fig. 6 is a horizontal section through a portion of 82 the cup on the dotted line 6—6 of Fig. 4; Fig. 7 is a top view of the cup in its stage of formation illustrated in Fig. 2; Fig. 8 is a top view of the completed cup represented in Fig. 4, Figs. 4 and 8 illustrating the cup as completed for the market; Fig. 9 is a side view of the completed cup after its lower end has been folded on the crease lines illustrated in Figs. 1 and 4 to create a flat bottom, the dotted lines in Fig. 9 indicating downwardly extending edge portions of the cup which are created by bending the central portion of the bottom of the cup upwardly preparatory to said edge portions being themselves bent inwardly toward each other, or to the position shown by full lines in Fig. 9, the crease lines in the flat cup guiding the user in forming the flat bottom in the cup; Fig. 10 is a sectional view through a portion of the cup at right angles to the sides thereof and illustrates by full lines one of the depending edge portions indicated by dotted lines in Fig. 9, and Fig. 11 is a bottom view of the cup as it appears after a user has folded in the lower end portions of the cup to create the flat bottom.

In the drawings 15 designates the blank

of waterproof paper or other suitable material, from which the cup is formed, said blank comprising two corresponding flat members 16, 17 and having a crease line 18 on one face defining the central transverse division between said members. The members 16, 17 have inwardly converging side edges extending to the ends of the crease line 18, and in addition the members 16, 17 are formed with crease lines 19, 20, 21, the crease lines 19 being transverse of the blank and equally spaced from the central transverse line 18, and the crease lines 20 being extended lengthwise of the blank parallel with each other from one crease line 19 to the other crease line 19 and reasonably adjacent to the side edges of the blank, while the crease lines 21 extend outwardly on inclined lines from the ends of the longitudinal crease lines 20 to the crease line 18. The crease line 18 defines the line on which the blank is folded, and the other crease lines referred to come into use only when a prospective user of the cup desires to convert the lower end of the same into a flat supporting bottom.

After the blank has been folded on the line 18 and the members 16, 17 have been brought in face to face contact, the adjacent side edge portions of said members are securely fastened together and flatwise against each other to form a flat receptacle by means of binding strips 22, preferably of metal, which extend from the upper to the lower edges of said members and are approximately of U-shape in cross-section to receive and be firmly compressed against said edge portions of the members 16, 17 so as to bind said members together without other means than the pressure of the opposite sides of said binding strips. Initially the binding strips 22 extend slightly above the upper edges of the members 16, 17 and thereby form projecting portions 23, as shown in Fig. 2. After the strips 22 have been applied to the side edges of the members 16, 17 to create the construction shown in Fig. 2, said binding strips are folded over or turned inwardly toward each other against the outer face of one of said members; in this instance the member 16, and the upper projecting end portions 23 of said binding strips are then bent laterally and downwardly against the inner face of said member 16, leaving the upper ends of the binding strips smooth and securing said strips against the outer face of the member 16, thereby creating the construction shown in Fig. 4. When the cup has reached the stage illustrated in Fig. 4, it will have been entirely completed and be ready for the market, the cup then being flat and formed of two integral sides fastened together at their vertical edges by the strips 22, with no paste or other adhesive present.

The finished cup discloses the crease lines 19, 20, 21 as a guide and aid to the user of the cup in fashioning the lower end thereof into a flat bottom adapted to support the cup on a table, tray or the like. The flat cups shown in Fig. 4 may be very conveniently carried both in stock by a dealer and in the pocket by persons desiring to use the cups. The cup shown in Fig. 4 is a flat cup as distinguished from what is commonly called a "formed-up" cup or one which is permanently in circular shape and has a fixed flat bottom. The paper used in the manufacture of my cup is flexible and of water-proof character and preferably devoid of any wax or other surface-coating.

When it is desired to use the cup of my invention a person may by pressing inwardly on the middle portion of the bottom edge thereof, cause the paper of the cup to bend at right-angles to the side members 16, 17 on those portions of the crease lines 19 which are intermediate the crease lines 20, as indicated in Fig. 10; and because of the presence of the crease lines 19 the material of the cup will readily flatten on said lines and in doing so draw the opposite side or bound edges of the cup slightly toward each other and open out or distend the main body portion of the bottom of the cup, and in addition the flattening of the central portion of the bottom of the cup will form and leave projecting downwardly from the fold lines 20, two triangular end sections 24 which may then be folded inwardly on the crease lines 20 and those portions of the crease lines 19 which are outwardly beyond the lines 20, against the flat portion defined between said lines 20 and the middle portions of the lines 19, a rectangular flat bottom being thus created, as shown in Fig. 11, suitable to support the cup and such contents as may be placed therein. The bendable metal strips 22 extend along the sections 24, and when said sections are folded inwardly to aid in creating the flat bottom, said strips serve to preserve the integrity of the flat bottom and thus materially aid in creating a durable structure and a cup of such stability as to render its use both convenient and safe.

My invention, therefore, comprises a desirable cup-structure which is initially flat, and which has on its side members guiding means or crease lines enabling a user to properly and conveniently convert the lower end of the cup into a flat supporting bottom which without any added means serves to maintain the cup in expanded condition ready for use.

What I claim as my invention and desire to secure by Letters Patent is:

1. As a new article of manufacture, an initially flat drinking cup of paper or the like comprising a transversely folded blank

the faces of whose side members are clamped together liquid tight at their adjacent side edges and bear adjacent to their lower ends crease lines to guide the user in converting 5 the lower end of the cup into a flat bottom on which the cup may stand.

2. As a new article of manufacture, an initially flat drinking cup of paper or the like comprising a transversely folded blank 10 the faces of whose side members are clamped together liquid tight at their adjacent side edges and bear adjacent to their lower ends crease lines to guide the user in converting the lower end of the cup into a flat bottom 15 on which the cup may stand, said crease lines extending transversely of said members suitably above the folded lower edge of the cup, vertically between said transverse lines inwardly from the side edges of said members and downwardly and outwardly from the upper ends of said vertical lines to the lower edge of the cup.

3. As a new article of manufacture, an initially flat drinking cup of paper or the like comprising a transversely folded blank 25 forming the side members of the cup, and bendable stiffening strips clamped upon and holding together liquid tight the adjacent side edges of said members, said members having adjacent to their lower ends 30 crease lines to guide the user in converting the lower end of the cup into a flat bottom on which the cup may stand.

4. An initially flat drinking cup of paper 35 or the like comprising a transversely folded blank forming the side members of the cup, and bendable stiffening strips applied to and binding together the adjacent side edges of said members, said members having adjacent to their lower ends 40 crease lines to aid the user in converting the lower end of the cup into a flat bottom, and said lines extending transversely of said members above the lower folded edge of the cup, vertically between 45 said transverse lines at points set inwardly from the vertical side edges of said members and diagonally downwardly and outwardly from the upper ends of said vertical lines to the lower edge of the cup.

5. As a new article of manufacture, an initially flat drinking cup of paper or the like comprising a transversely folded blank forming the side members of the cup, and bendable stiffening strips clamped upon and holding together liquid tight the adjacent 55 side edges of said members, said members having adjacent to their lower ends crease lines to guide the user in converting the lower end of the cup into a flat bottom on which the cup may stand, and said strips 60 being of metal and of U-shape in cross section and receiving between their side portions the face-to-face edge portions of said cup-members.

6. As a new article of manufacture, a drinking cup of paper or the like comprising a transversely folded blank constituting the opposite side members of the cup, and stiffening strips clamped upon and holding together liquid tight the adjacent side edges 70 of said members, said strips being folded over inwardly parallel with said members and having their upper ends which normally project above said members bent laterally and downwardly against the inner face of 75 the member whose outer face is engaged by them.

7. As a new article of manufacture, a drinking cup of paper or the like comprising a transversely folded blank constituting 80 the opposite side members of the cup, and bendable strips clamped upon and holding together liquid tight the adjacent side edges of said members, said strips being of metal and of U-shape in cross section and receiving 85 between their side portions the face-to-face edge portions of said cup-members, and the bottom fold of the blank being exposed and free to be manipulated by the user in creating a flat bottom for the cup. 90

Signed at New York city, in the county of New York and State of New York, this 8th day of July A. D. 1913.

ELIJAH F. SPAULDING.
